METHOD AND APPARATUS FOR FORMING
CORES

Edgar A. Petersen, Grosse Pointe, Mich., assignor
to Chrysler Corporation, Highland Park, Mich.,
a corporation of Delaware

Application January 26, 1942, Serial No. 428,182

12 Claims. (Cl. 22—10)

This invention relates to improvements in the art of making cores to be used in casting metallic articles of manufacture.

More particularly, the invention relates to the making of sand cores for casting pistons of the type used in internal combustion engines although the invention in its broad aspects is not so limited.

An object of the invention is the provision of improved method and apparatus for the making of sand cores by introducing the core-forming sand under pressure into a cavity of the core-forming apparatus in a manner which facilitates relative separation or drawing of the molding apparatus.

A piston for use in an internal combustion engine has reinforcing ribs on the internal surface, such ribs being provided for both the head and skirt portions of the piston. Formation of these ribs and the conventional wrist pin bosses requires a core-forming apparatus which has therein parts drawn transversely to the core while other parts, such as the rib-forming grooves in the core, necessitate a draw in a direction axially with respect to the core.

It is advantageous in the making of these cores to employ the sand blasting method rather than hand packing and to so introduce the core-forming sand into the molding cavity that the same will not become lodged or wedged between parts of the apparatus as to prevent the relative separation of these parts with ease.

Core making apparatus includes an open print end and an axially opposite covered end through which vanes or fingers extend into the core-molding cavity for forming grooves in the core, these grooves in turn forming the reinforcing ribs. When the core-forming sand was admitted through the print end under pressure it was found that sand lodged between the vanes and the slots in which they were slidably received and after a number of cores were thus formed this sand acted as a wedge and prevented these parts from being relatively separated.

I have found that by admitting sand through the normally covered end, opposite the print end, the aforesaid difficulties have been overcome and that relative separation of the vanes or fingers from the cavity is made with ease, the wedging action of the same being no longer present. When the foregoing is practiced there is added a squeezing operation by inserting a suitable tool through the blow opening in the covered end to imprint the adjacent end face of the core without interrupting the contour imparted to this

end face by the face of the cover and the vanes or fingers.

For a more complete description of the method and apparatus, reference is made to the accompanying drawings in which:

Fig. 1 is an elevational view, partly in section, of a piston made according to the principles of the invention.

Fig. 2 is a sectional view taken as indicated by the line 2—2 of Fig. 1.

Fig. 3 is an end view taken as indicated by the line 3—3 of Fig. 1.

Fig. 4 is a transverse section through a mold showing the core located therein for casting of the piston.

Fig. 5 is a side elevational view illustrating the core forming apparatus.

Fig. 6 is a top plan view, partly in section, taken on line 6—6 of Fig. 5.

Fig. 7 is a fragmentary section taken on line 7—7 of Fig. 6.

Fig. 8 is a side elevational view, partly in section, taken on the line 8—8 of Fig. 6.

Fig. 9 is a sectional view taken on line 9—9 of Fig. 5.

Fig. 10 is a side elevational view, partly in section, and similar to Fig. 5, with the groove forming vane being removed and the imprinting tool shown in operating position.

Referring to Figs. 1, 2 and 3, the numeral 15 designates a piston for an internal combustion engine. The piston has ring-receiving grooves 16 in the head thereof and wrist pin bosses 17. The piston is reinforced by a plurality of ribs on the inner surface thereof including the circumferential ribs 18 connecting the bosses 17, and a plurality of axially extending ribs 19 which also appear on the inner face of the closed end of the piston and which intersect the annular rib 20 on the latter face. The end face of the piston has a centrally located depression at 21 for lathe centering during machining of the casting, the thickness of the end being increased by an internal boss 22 registering with the depression 21. The core used in casting the piston 15 is outlined by the dash lines in Figs. 1 and 2.

The core, generally designated by the numeral 23, used in casting the piston is more particularly shown in Fig. 4 and has the axial grooves 24 in the side walls and top face thereof, which form the reinforcing ribs 19, and the circumferential groove 25 which forms the annular rib 18. The core has the print 26 for locating the same in the mold.

The apparatus for molding or forming the core

23 is shown in Figs. 5 to 10 and includes the complementary parts 27 and 28 cooperating to form a core box having a mold cavity 29, these parts being detachably secured together at adjacent ends by bolts 30. Each of these parts has a portion 31 secured thereto by screws 32, as illustrated in Fig. 10, which portions are diametrically opposed and form openings in the core 23, these openings receiving a core 33 to provide the wrist pin bosses 17 of the piston. The diameter of the cavity 29 is reduced at the upper end thereof, as indicated at 34 to provide the core portion 35 which in turn forms that portion of the piston having the grooves 16.

The wall of each part 27, 28 bounding the cavity 29 has a plurality of grooves 36 therein extending axially with respect to the cavity 29. A vane or finger 27 is slidably received in each groove 36, and projects into the cavity 29 to form a groove in the side wall and end face of the core. The parts 27, 28 are provided with a pair of locating rods 33. The core box is vented as at 29.

The mold cavity 29 has a print end 39, forming the core print 26, and an axially opposite end provided with a cover 40 having spaced slots 41 therethrough respectively registering with the grooves 36 for receiving a vane or finger 36. It will be noted that the end portion of each vane 36 has an increased width at the covered end 40 to thereby extend a greater distance into the cavity to form the groove 24 in the end face of the core 23. Each vane 37 is secured to a draw plate 41 overlying the cover 40 by a screw 42. The inner face of the cover 42 has an annular rib 43 which forms an annular depression in the adjacent end face of the core, which core depression provides the rib 20 for the piston.

It will be apparent that the vanes 37 are withdrawn from the cavity 29 and through the cover 40 by relatively moving the plate 41 and vanes 37 relative to the parts 27, 28 in a direction axially with respect to the cavity 29, while the parts 27, 28 are relatively separable in a direction transverse to the cavity.

In making the core by the sand blasting method it was found that by thus introducing the mold forming sand into the cavity 29 through the print end 39 the sand became lodged between the vanes and their groove walls, and particularly so at the cover 40 and after a small number of cores were blown this sand acted as a wedge to prevent drawing of the vanes. It was found this difficulty could be overcome and the benefits of the sand blasting method availed of by introducing the core forming sand through the covered end of the core, it being understood that the print end 39 rested upon a suitable support (not shown) to retain the sand in the cavity.

For the foregoing purpose the cover 40 is provided with a blow hole 44 receiving a sand conducting conduit 45. The latter and the plate 41 are movable by an operating member 46. The wall bounding the opening 44 is provided with an annular pointed rib 47 controlling the height of the core forming sand and provides a sharp and distinct portion at the adjacent portion of the core. In Fig. 8 the cavity 29 is shown partially filled, it being understood that the cavity is filled to form the core as illustrated by the dotted lines. After filling of the cavity 29 the vanes 37 are withdrawn from the cavity through the cover member 40 and a suitable tool 48 having an end defining a portion of a sphere is inserted through the blow hole 45 of the cover 40

to imprint the adjacent end face of the core by forming a depression therein. This constitutes a squeezing operation by which the sand adjacent the blow opening is packed, the cover remaining in place to otherwise prevent interruption of the contour of the end face during the squeezing or packing operation. The depression thus formed in the core provides the central piston boss 22. The tool 48 is then removed and the remaining parts 40, 27 and 28 relatively separated. The piston is then cast by placing the core in a suitable mold as illustrated in Fig. 4.

It will be understood that the vanes 37 can be separated by moving the core box forming parts 27, 28 while the vanes are stationary or that the latter parts can remain stationary and the vanes moved. In either instance the vanes pass through the covered end of the cavity. The invention also contemplates that means other than the operating member 46 can be utilized in conjunction with the apparatus for drawing the vanes.

Although but one embodiment of the invention is herein shown and described, it will be understood that various changes in the size, shape and arrangement of parts may be made without departing from the spirit of my invention and it is not my intention to limit said invention other than by the terms of the appended claims.

I claim:

1. The method of forming a core in a core box having a print end, which comprises moving a cover and vanes axially into closing and inserted relationship respectively with respect to the end of the mold cavity opposite to said print end, filling said mold cavity from the end thereof opposite to said print end by introducing a blast of sand through said cover into said cavity, and producing relative movement between said vanes and core box to thereby withdraw said vanes from said cavity in a direction axially with respect to the cavity.

2. The method of forming a core in a core box having a print end, which comprises moving a cover and vanes axially into closing and inserted relationship respectively with respect to the end of the mold cavity opposite to said print end, filling said mold cavity from the end thereof opposite to said print end by introducing a blast of sand through said cover into said cavity, producing relative movement between said vanes and core box to thereby withdraw said vanes from said cavity in a direction axially with respect to the cavity, and moving a tool through said cover while the latter is engaged with the core to imprint the end face of the core adjacent said cover.

3. The method of forming a core in a core box including a mold cavity, a print end and a cover at the end of the cavity opposite the print end, which comprises projecting vanes through said cover into said cavity, admitting a blast of core-forming sand through said cover into said cavity, and withdrawing said vanes from said cover and said cavity by relative separation thereof in a direction axially with respect to the cavity.

4. The method of forming a core in a core box including a mold cavity, a print end and a cover at the end of the cavity opposite the print end, which comprises projecting vanes through said cover into said cavity, admitting a blast of core-forming sand through said cover into said cavity, withdrawing said vanes from said cover and said cavity by relative separation thereof in a direction axially with respect to the cavity, and insert-

ing a tool through said cover while the latter is engaged with the core to imprint the end face of the core adjacent the cover.

5. The method of forming a core in a core box, including a mold cavity, a print end, a removable cover for the end of the cavity opposite the print end, and a draw member having vanes extending through the cover into the mold cavity, which comprises, introducing core-forming sand under pressure through said cover into said cavity, and producing relative movement between said draw member and said core box in a direction axially with respect to the mold cavity to thereby withdraw said vanes from said cavity through said cover.

6. The method of forming a core in a core box including a mold cavity, a print end, a removable cover for the end of the cavity opposite the print end, and a draw member having vanes extending through the cover into the mold cavity, which comprises, introducing core-forming sand under pressure through said cover into said cavity, producing relative movement between said draw member and said core box in a direction axially with respect to the mold cavity to thereby withdraw said vanes from said cavity through said cover, moving a tool through said cover while the latter is engaged with the core to imprint the end face of the core adjacent said cover, and removing said cover.

7. In a method for forming a core in a core box including relatively separable parts forming a mold cavity having a print end, a removable cover for the cavity opposite the print end and vanes removably extending through said cover into said cavity, which comprises, introducing a blast of core-forming sand through said cover into said cavity, relatively moving said vanes and mold cavity forming parts to thereby withdraw said vanes from said cavity through said cover, inserting a tool through said cover while the latter is engaged with the core to imprint the end face of the core adjacent said cover, removing said cover, and relatively separating said parts in a direction transverse to the core.

8. The method of forming a core in a mold cavity including a print end and an opposite covered end having a blow hole, which comprises moving vanes into said cavity through the covered end thereof, introducing core-forming sand under pressure into said cavity through said blow hole, withdrawing said vanes from said cavity, and packing the core-forming sand adjacent the blow hole by a total inserted through said blow hole.

9. In an apparatus for molding a piston-forming core having surface grooves, a core box having a cavity and comprising, parts relatively separable only in a direction transverse to the cavity, each of said parts having a slot in the wall thereof bounding the cavity and extending axially with respect to the latter, a cover for one end of said cavity having slots therethrough respectively registering with the first mentioned slots, groove-forming vanes respectively slidably received in

said registering slots and having portions thereof respectively projecting from said cover and walls into said cavity, and a draw plate overlying said cover secured to said vanes, said cover and said plate having registering openings for admitting a blast of sand in an axial direction into said cavity, said plate and said vanes being relatively separable from said cover, core box and the core in an axial direction with respect to said cavity.

10. Apparatus for forming a sand core by sand blasting, comprising, a core box having a sand-receiving cavity and a print end, said box including parts relatively separable in a direction transverse to said cavity, cover means for the end of said box opposite said print end including a first member having slots extending therethrough and a second member movable relative to the first member, vanes carried by said second member respectively extending through the slots in said first member and projecting into said cavity, said members having an inlet opening therethrough for admitting a blast of sand axially into said cavity, said second member and said parts being relatively movable in an axial direction with respect to said cavity for withdrawing said vanes from said first member and said cavity, and a die member insertable through the opening in said first member for imprinting the adjacent end face of the core.

11. Apparatus for forming a sand core by sand blasting, comprising, a core box having a sand-receiving cavity, said box including parts relatively separable in a direction transverse to said cavity, each of said parts having a vane-receiving slot in that face thereof bounding said cavity and extending axially with respect to the latter, a draw plate associated with one end of said cavity, vanes carried by said plate and respectively slidably disposed in said slots, said plate having an opening therein for admitting a blast of sand into said cavity in a direction axially thereof, said plate and said vanes being movable relative to said core in a direction axially with respect to the cavity for withdrawing said vanes from said cavity.

12. Apparatus for forming a sand core by sand blasting comprising a core box having a sand-receiving cavity, said box including parts relatively separable in a direction transverse to said cavity, each of said parts having a vane-receiving slot in that face thereof bounding said cavity and extending axially with respect to the latter, a cover for said cavity having slots therethrough adapted to register with the respective slots of said cavity, a draw plate extending over said cover, vanes carried by said draw plate and respectively slidably disposed in said registering slots, said cover and said draw plate having registering openings therein for admitting a blast of sand into said cavity, said draw plate and said vanes being movable relative to said parts in a direction axially with respect to said cavity for withdrawing said vanes from the latter.

EDGAR A. PETERSEN.
